UNITED STATES PATENT OFFICE.

ALBERT HENRY LEACH, OF LOS ANGELES, CALIFORNIA.

DESIGN FOR A SINK SCRAPER AND CLEANER.

SPECIFICATION forming part of Design No. 34,241, dated March 19, 1901.

Application filed February 13, 1901. Serial No. 47,190. Term of patent 3½ years.

To all whom it may concern:

Be it known that I, ALBERT HENRY LEACH, a citizen of the United States, residing at Los Angeles, in the county of Los Angeles and State of California, have produced a new and original Design for a Sink Scraper and Cleaner, of which the following is a specification.

This invention relates to a new and original design for a sink scraper and cleaner, and the essential feature resides in the design illustrated in the accompanying drawings, wherein—

Figure 1 is a perspective view of a sink scraper and cleaner embodying the features of the invention. Fig. 2 is a longitudinal vertical section of the same.

The design is characterized by an elongated compound-curved flat member 1, having a

right-angular head 2 at one extremity, provided with a back rib 3, extending in a longitudinal direction relatively to the head and formed with a rear curved edge 4. The front side or face of the head is provided with a series of intersecting angular grooves 5, which produce diamond-shaped parts 6.

Having thus described the invention, what is claimed as new is—

The design for a sink scraper and cleaner, herein shown and described.

In testimony that I claim the foregoing as my own I have hereto affixed my signature in the presence of two witnesses.

ALBERT HENRY LEACH.

Witnesses:

GEO. P. REID,
R. A. HEFFNER.
